POWER LAWN MOWER

Acial L. Cataline, Lansing, and Lawrence H. Wilson,
Detroit, Mich., assignors to Motor Wheel Corporation,
Lansing, Mich., a corporation of Michigan

Application August 22, 1955, Serial No. 37,599

Term of patent 7 years

(Cl. D40—1)

FIG. 1

FIG. 2

FIG. 3

FIG. 4

FIG. 5

FIG. 6

Fig. 1 is a perspective view of a power lawn mower, showing our new design, the handle being broken away for convenience of illustration.

Fig. 2 is a side elevational view of the housing as viewed from the left of Fig. 1.

Fig. 3 is a fragmentary sectional view along the line 3—3 in Fig. 2.

Fig. 4 is a plan view.

Fig. 5 is a rear elevational view.

Fig. 6 is a fragmentary sectional view along the line 6—6 in Fig. 4.

The characteristic features of the design reside in the housing shown in full lines.

We claim:

The ornamental design for a power lawn mower, as shown and described.
